ADJUSTABLE READING STAND

Lila Lee Fuller, Houston, Tex.

Application May 6, 1946, Serial No. 667,658

5 Claims. (Cl. 45—61)

1

This invention relates to an adjustable reading stand.

An object of the invention is to provide an adjustable reading stand including a holder for a book, magazine, or other reading matter and which may be adjusted vertically and laterally, as well as about a horizontal axis so that the stand can be adjusted to suit the convenience of the reader.

The stand has been designed particularly for the convenience of patients, when in a reclining position and specially for those who cannot conveniently hold the book or other reading matter and turn the leaves as reading progresses.

While the reading stand herein described has been primarily designed for disabled patients it is capable of general use for the convenience of readers either in reclining or sitting-up position.

A still further object of the invention is to provide an adjustable reading stand which may be easily folded into a very compact position for storage or transportation.

With the above and other objects in view the invention has particular relation to certain novel features of construction, arrangement of parts and use, an example of which is given in this specification and illustrated in the accompanying drawings, wherein:

Figure 1 is an elevational view of the stand.

Figure 2 is an enlarged, fragmentary, cross-sectional view taken on the line 2—2 of Figure 1.

Figure 3 is an enlarged, fragmentary, cross-sectional view taken on the line 3—3 of Figure 2.

Figure 4 is a side, elevational view.

Figure 5 is a plan view partly in section taken on the line 5—5 of Figure 4; and

Figure 6 is an enlarged, cross-sectional view taken on the line 6—6 of Figure 4.

Referring now more particularly to the drawings wherein like numerals of reference designate the same parts in each of the figures, the numeral 1 designates the supporting base which is, preferably, formed of tubular metal bent into a U-shape, as more clearly shown in Figure 5, and which is provided with a cross-brace 2 welded or otherwise secured to the side members of the base 1. The base is preferably supported on suitable casters 3 whereby it is rendered readily portable in use.

Mounted on the cross-brace 2 and upstanding therefrom there is the tubular post 4 whose upper end is longitudinally slotted to render it contractile and whose lower end is formed with a bearing 5 through which the cross-brace 2 extends.

2

There is a clamp collar 6 around the post having free outwardly turned ends and there are the angle-braces 7, 7 whose lower ends are pivoted to the respective side members of the base 1 and whose upper ends fit against the outwardly turned ends of the clamp collar 6. A clamp bolt 8 is fitted through suitable registering holes in the upper ends of the angle-braces 7 and the outwardly turned ends of the clamp collar 6, one end of this bolt being provided with a head and its other end being threaded to receive the wing nut 9.

By tightening up on the nut 9 the clamp collar 6 will securely clamp the post 4 and hold it in any desired upright position. However when the clamp nut 9 is loosened the post may be folded downwardly in the direction of the arrow a in Figure 1, the clamp collar 6 moving upwardly along said post until the post is brought into parallel relationship with the base 1 and maintained in that position by again tightening up on the nut 9.

There is a supporting rod 10 whose lower end is telescoped into the upper end of the post 4. Surrounding said upper end there is a clamp collar 11 whose free ends are outwardly turned and fitted between said free ends there is a cam 12 which rotates on a bolt 13 which is fitted through the outwardly turned ends of the clamp collar 11 and through said cam. The cam is provided with a handle 14 by means of which it may be operated into clamping, or released, position.

When the cam 12 is released the rod 10 may be adjusted up or down and said cam may then be actuated to active position, as shown in Figure 1, to cause the clamp collar 11 to contract the upper end of the post 4 into clamping relation with the rod 10.

The upper end of the rod 10 is provided with a fork 15 and mounted on the rod beneath said fork there is a hinge member 16 having upwardly turned lugs, as 17, between which one end of the supporting arm 18 is pivoted. This arm rests in the fork 15 and is supported in horizontal position thereby. However when it is desired to collapse the stand the arm 18 may be swung around in the direction indicated by the arrow b, in Figure 1, and will hang in parallel relationship with the post 4.

The free end of the arm 18 may be reduced in diameter and overturned at right angles and terminates in a ball bearing member 19. There is a plate like book holder 20 preferably formed

of thin metal and preferably substantially rectangular in shape.

Fastened to the lower margin of it there is a forwardly turned flange 21 which is co-extensive in length, with the holder 20 and which forms a support for a book, as 22, on the holder. This holder is of sufficient length so that the ordinary book, or magazine, may be maintained on it in open position.

Fastened to the rear side of the holder 20, approximately midway between its ends, and upstanding therefrom, there is a bar 22a whose upper end is slightly forwardly turned and fastened to said upper end, and extending forwardly approximately horizontally there is a bracket 23 to the free end of which a light globe hood 24, of any selected design, is pivoted.

For the purpose of adjusting said hood as required by the patient a link 25 has its forward end pivotally connected to said hood and this link is provided with an oblong slot 26. A clamp screw 27 having an enlarged head passes through the said slot 26 and is screwed into the bracket 23. This screw may be loosened and the hood 24 adjusted as desired and the screw 27 then tightened up to secure said adjustment.

A conventional light globe, as 28, may be screwed into a socket provided for the purpose in the hood 24 and an electric current may be carried to the light globe through the electrical conductors 29 leading from a wall socket or other source of electricity. The electrical conductors 29 may be supported on the arm 18 by suitable clips 30 provided for the purpose.

Fastened to the rear side of the holder plate 20, approximately midway between the upper and lower margins thereof are the longitudinal bars 31, 31 which extend from the outer ends of the plate inwardly to approximately the center thereof and the inner ends of these bars are rearwardly turned and formed into clamps 32, 32 which are concavo-convex and which embrace, and grip, the ball bearing 19. They are maintained in said gripping relation by means of a clamp bolt 33 which extends through said clamps and which has a head on one end and a clamp nut threaded onto the other end whereby said clamps may be maintained in clamping relation with the ball bearing 19, or released, to permit removal or adjustment of the book holder.

The outer ends of the respective bars 31 are spaced from the holder plate 20 by the spacers 34 but are secured thereto by means of the bolts 35 which pass through the plate 20, the spacers and the corresponding ends of said bars 31. The inner ends of the bars 31 are spaced from the plate 20 by means of the spacers 36 and opposite these spacers, in front of the holder 20, there is a clamp plate 37. Clamp bolts 38, 38 pass through the clamp plate 37, through the holder 20, the spacers 36 and the inner ends of the bars 31 and hold these parts in assembled relation.

In front of the bars 31, 31 the plate 20 is provided with longitudinal slots 39, 39. There are the anchors, as 40, which slide against the forward side of the plate 20 and which have the reduced necks 41 which fit through the corresponding slots 39 and fitted against the rear side of the holder plate 20 are the slide plates 42 which are fastened to the corresponding anchors 40 by set screws, as 43.

Extending outwardly from each anchor 40 there is an arm 44. Extending forwardly from the outer end of each arm 44 and rigidly secured

thereto there is a guide rod 45, the outer end of said rods terminating in enlarged heads 46.

There are the clamp arms 47, the outer ends of said arms having bearings to receive the rods 45, said clamp arms being slideable on said rods 45 and surrounding the rods 45 and interposed between the clamp arms and the corresponding heads 46 are the coil springs 48.

The inner ends of the clamp arms 47 carry the 10 clamps 49 which are elongated and extend at right angles to the clamp arms 47. These clamps are designed to rest against and hold the outer margins of the leaves of the books, or magazine, and are held in yielding contact therewith by the 15 pressure of the springs 48 so as to maintain the leaves in open position.

The outer ends of the clamp arms 47 are provided with the oppositely disposed finger grips 50 for the purpose of releasing the clamps 49 for 20 convenience in turning or adjusting the leaves of the book. By placing the thumb on a head 46 and engaging the finger grips 50 with the fingers the clamp arm 47 and the corresponding clamp 49 may be pulled outwardly, or released, from the leaves 25 so as to permit turning, or shifting, of the leaves as desired.

Fastened to each clamp arm 47 there is a spring clamp 51. The free ends of these clamps 51 are turned inwardly and they are provided for convenience in turning the leaves of the book. As a leaf is turned its free margin may be temporarily inserted under the corresponding spring clamp 51 so as to hold the leaf in place until it becomes necessary to shift the leaves underneath the 35 clamps 49 which may be done, as hereinabove explained.

The clamp means for holding the book or magazine open may be readily adjusted to accommodate books and magazines of different sizes.

40 In order to hold the book, or magazine, firmly in position on the holder plate 20 a rod 52 has been provided. The lower end of this rod is pivoted to the forwardly turned flange 21, approximately midway between its ends and the upper end of the rod may be engaged with a hook 53 secured to the upstanding bar 22a above the book holder 20, as best shown in Figures 4 and 6, and so the rod 52 may be readily released for turning leaves or whenever desired.

50 As is obvious the book holder and the appendants thereof may be readily detached by loosening the bolt 33 and the other parts of the stand may be folded together in collapsed position in the manner hereinabove explained.

55 The drawings and description are illustrative merely while the broad principle of the invention will be defined by the appended claims.

What I claim is:

60 1. In a reading stand, a plate-like book holder having aligned, longitudinal slots, a book support at the lower margin of the holder, anchors movable along the forward side of the holder and which are provided with reduced necks which extend through said slots, slide plates movable 65 along the rear side of said holder and attached to said necks, an arm extended outwardly from each anchor, a guide rod rigidly secured to, and extending forwardly from each arm, a clamp arm having a slideable bearing on each guide rod and 70 extended inwardly therefrom, a leaf clamp on the inner end of each clamp arm and a yieldable element acting against each clamp arm and effective to hold the leaf clamps in yielding engagement with the leaves of an open book on the 75 holder.
